ABSTRACT

An ignition coil has a secondary winding wound on a coil and a primary winding which is co-axial with the secondary winding and is spaced therefrom by a layer of corrugated electrically insulating material defining a plurality of channels extending parallel to the axis of the core. At least one layer of the primary winding is wound on the secondary winding between the secondary winding and the layer of corrugated electrically insulating material.

IGNITION COILS

This invention relates to ignition coils for use in spark ignition systems for road vehicles.

An ignition coil according to the invention includes a secondary winding wound on a core, and a primary winding which is co-axial with the secondary winding, the primary winding being spaced from the secondary winding by a layer of corrugated electrically insulating material defining a plurality of channels extending parallel to the axis of the core, characterized in that at least one layer of the primary winding is wound on the secondary winding between the secondary winding and the layer of corrugated electrically insulating material.

An example of the invention is illustrated in the accompanying drawings, in which:

FIG. 1 is a longitudinal section through an ignition coil, and

FIG. 2 is a section on the line 2—2 in FIG. 1.

Referring to the drawings, the coil includes a generally cylindrical metal casing 10 having an integral base at one end, and closed at the other end by a moulded insulating cap 11. The cap 11 carries the low tension terminals 12, 13 and high tension terminal 14 of the ignition coil, and extending axially within the casing between the cap 11 and an insulating support 15 engaged with the base of the casing is a laminated iron core 16. Surrounding the core is a cylindrical, card-board or similar electrically insulating former 17, and wound on the former is the secondary winding 18 of the ignition coil. The wire constituting the secondary winding 18 is coated with a varnish so that adjacent convolutions of the winding are insulated from one another, and adjacent layers of the secondary winding 18 are in addition insulated from one another by intermediate layers of insulating paper.

Surrounding the secondary winding is one layer 20 of the primary winding 21 of the coil. The wire of the primary winding is provided with a coating of insulating varnish, and the layer 20 is further insulated from the secondary winding 18 by means of several insulating paper layers (not shown). Surrounding the layer 20 is a cylindrical electrically insulating single layer 19 formed from corrugated paper wrapped around the layer 20, the corrugations of the layer 19 extending parallel to the core 16. A suitable paper is the flexible paper sold under the trade name "Carbion". Wound on the corrugated layer 19 is the remainder of the primary winding 21 of the coil, and as in the case of the secondary winding, adjacent layers of the primary winding are insulated from one another not only by the varnish, but also by intermediate layers of insulating paper. An additional layer (not shown) of paper is provided to insulate the winding 21 from an iron shield 22 lining the casing 10. The winding 21 is of course continuous and extends through the layer 19.

The primary winding 20, 21 is formed from a relatively few turns of relatively thick wire, while the secondary winding 18 is formed from a relatively large number of turns of relatively thin wire. The wire of the primary winding is sufficiently thick to enable connections to be made thereto quite easily, but the wire of the secondary winding is too thin to permit connections to be made satisfactorily, and so the ends of the secondary winding are electrically connected during manufacture of the windings to a pair of conductive braids. The end

of the primary winding defined by the layer 20 and the one end of the secondary winding 18 are electrically interconnected and are connected to the terminal 12. The other end of the secondary winding is electrically connected to the terminal 14 through the core 16 of the coil, and a spring 23 which also locates the core in position. The other end of the primary winding is electrically connected to the terminal 13. The terminal 12 is connected in use through the contact breaker of an ignition system to earth, the terminal 14 is connected to the rotor arm of an ignition distributor of the system, and the terminal 13 is connected to one terminal of the battery, the other terminal of which is earthed. The free volume in the casing is filled with oil which acts as a coolant for the coil. It will of course be appreciated that the two parts 20, 21 of the primary winding are interconnected through the layer 19.

It will be appreciated that since the corrugations of the layer 19 between the primary and secondary windings extend axially, in a direction parallel to the core, then axially extending passages are defined within which in use the oil filling the casing can circulate. In this way, the windings of the coil are more efficiently cooled than those of a comparable ignition coil formed without the corrugated layer 19. Moreover, the corrugated layer 19 spaces the main part of the primary winding from the secondary winding and thereby ensures that the magnetic coupling between the primary and secondary windings is looser than the coupling between the primary and secondary windings in a comparable coil formed without the corrugated layer 19. The looser magnetic coupling between the windings gives rise to a decrease in the time taken for the voltage in the secondary winding to reach its peak value as compared with conventional coils, and this means that less energy is dissipated in spurious resistive loads occurring between the terminal 14 and earth. Such loads can be caused, for example, by condensation, dirt or products of combustion given off by the engine. The loose coupling reduces the risk of an inadequate spark being produced under such conditions, so rendering the coil more reliable than conventional coils, particularly in cold conditions.

The reason for having at least one layer of the primary winding wound on the secondary winding, with the remainder of the primary winding spaced from the secondary winding, is that it has been found that in this way damage to the coil by voltage transients in the system is minimized. It is believed that in a conventional coil without the layer 19, transients are conducted from the secondary winding to the primary winding as a result of the relatively low impedance capacitive connection within the coil between these windings in addition to the physical low resistive electrical connection which exists between the windings. If the windings are entirely separated by the layer 19, this capacitive connection is greatly reduced, and so the transients can cause damage. By having part of the primary winding wound directly on the secondary winding, the advantages of the sleeve 19 are retained, and there is still a low impedance capacitive path which minimizes the risk of damage by the transients.

I claim:

1. A ignition coil including a hollow casing, a cap closing said casing and carrying the terminals of the

coil, a core extending axially within said casing, a secondary winding wound on said core, and a primary winding which is co-axial with the secondary winding, the primary winding having at least one layer wound on said secondary winding, but the remainder of the primary winding being spaced from said one layer and the

secondary winding by a layer of corrugated electrically insulating material defining a plurality of channels extending parallel to the axis of the core, and means connecting said windings to said terminals.
